US00D760267S

(12) **United States Design Patent**
Butcher et al.

(10) **Patent No.:** **US D760,267 S**
(45) **Date of Patent:** **** Jun. 28, 2016**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Gary Butcher**, San Jose, CA (US);
Graham Clarke, Mountain View, CA (US); **Craig Dehner**, San Francisco, CA (US); **Alan C. Dye**, San Francisco, CA (US); **Bradley Griffin**, Cupertino, CA (US); **Cyrus Irani**, Los Altos, CA (US); **Jonathan P. Ive**, San Francisco, CA (US); **Pedro Mari**, Santa Cruz, CA (US); **Henrique Penha**, San Francisco, CA (US); **Andre Souza Dos Santos**, Santa Clara, CA (US); **Christopher Wilson**, San Francisco, CA (US)

(73) Assignee: **Apple Inc.**, Cupertino, CA (US)

(**) Term: **15 Years**

(21) Appl. No.: **29/529,236**

(22) Filed: **Jun. 4, 2015**

(51) LOC (10) Cl. **14-04**

(52) U.S. Cl.

USPC **D14/486**

(58) **Field of Classification Search**

USPC **D14/485-495**

CPC .. G06F 3/0482; G06F 3/0481; G06F 3/04883

See application file for complete search history.

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with graphical user interface showing our new design. The broken lines in the FIGURE show a display screen or portion thereof, and form no part of the claimed design.

1 Claim, 1 Drawing Sheet
